United States Patent Office.

NICHOLAS S. VEDDER, OF TROY, AND TOBIAS S. HEISTER, OF LANSINGBURG, NEW YORK, ASSIGNORS TO NICHOLAS S. VEDDER.

Design No. 4,244, dated July 19, 1870.

DESIGN FOR STOVE-PLATES.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer and State of New York, have jointly invented and produced certain new and original features in Designs for Stove-Plates, of which the following is a specification, reference being had to the accompanying photographic representation of a cooking-stove having our new design.

One distinguishing feature of our said design is the compound ornament I, having its various parts shaped and arranged together, and cast upon and with a door or doors, or a plate or plates of a stove, so as to present the appearance represented in and by the aforesaid photograph.

Another feature of our said design is the combination of the aforesaid compound ornament I and ornamental border-molding J, all shaped and arranged and cast upon a door or doors, or a plate or plates of a

stove, with or without an intervening molding, k, so as to appear as shown in and by the aforesaid photographic representation.

What we claim as our invention and production, and desire to secure by Letters Patent, is—

1. The compound ornament I, having its various parts shaped and arranged together, and cast upon a plate or plates of a stove, as herein shown and described.
2. The combination of the compound central ornament I and ornamental border-molding J, all shaped and arranged upon and cast with a door or doors or a plate or plates of a stove, as herein described and shown.

NICHOLAS S. VEDDER.
TOBIAS S. HEISTER.
